UNITED STATES PATENT OFFICE.

EDWARD P. HAFNER AND JOHN T. ROBERTS, OF ST. LOUIS, MISSOURI.

ANTISKID DEVICE.

1,204,863.

Specification of Letters Patent. Patented Nov. 14, 1916.

Application filed February 9, 1916. Serial No. 77,261.

To all whom it may concern:

Be it known that we, EDWARD P. HAFNER and JOHN T. ROBERTS, citizens of the United States, residing at St. Louis, State of Missouri, have invented certain new and useful Improvements in Antiskid Devices, of which the following is a full, clear, and exact description, reference being had to the accompanying drawings, forming a part hereof.

10 Our invention has relation to improvements in anti-skid devices for vehicle wheels; and it consists in the novel features of construction more fully set forth in the specification and pointed out in the claim.

15 The object of our invention is to provide a vehicle wheel with an anti-skid device which can be readily applied about the tire of the wheel; one which shall be simple, cheap, durable, devoid of complicated details such as clamps, bolts, movable securing devices, and one possessing further and other advantages fully apparent from the following detailed description of the invention in connection with the accompanying drawings in which—

Figure 1 represents a side elevation of one-half of a vehicle wheel showing our invention applied thereto; Fig. 2 is an enlarged cross-section on the line 2—2 of Fig. 1; and 30 Fig. 3 is a detached inner plan of the chain anchoring plate with the terminal links of the chain shown in engagement with the plate.

Referring to the drawings, S, represents 35 the spoked portion of a vehicle-wheel, R, the felly, B, the sectional felly band, and T, the tires, a pair of tires being employed in the present embodiment of our invention, though of course we do not wish to be restricted in the application of our invention 40 to any particular construction of wheel.

Disposed at convenient points along the felly R, are plates or anchors 1, the same being substantially oblong in shape and 45 mounted lengthwise across the felly as shown (Fig. 2). One end of the anchor-plate terminates in an elongated hook 2, the opposite end terminating in an open eye 3, the clearance a between the free end of the loop 50 forming the eye and the plate being just sufficient to allow for the passage into the eye of the adjacent terminal oblong link 4 of the anti-skid chain 5. The members 2 and 3 are oppositely disposed along the longitudinal axis of the plate 1, the elongation 55 of the hook 2 being in the line of said axis,

the hook being substantially parallel to the plate so as to leave a deep open pocket or recess b with substantially U-shaped bounding walls, said pocket receiving the adjacent terminal circular ring 6 of the chain. The anchor 1 is secured in place in any suitable mechanical manner, that preferred being a pair of screws 7, 7 as shown, for the reception of which the anchor is provided with 60 openings h, h (Fig. 3).

In applying the chain (of which there may be any number) the ring 6 is first passed over the hook 2 into the pocket b, there being just sufficient slack in a chain length to 65 allow the chain to be drawn around the tires T, T, and permit the link 4 to be passed over the loop 3 and brought opposite the clearance a, the link slipping to the bottom of the eye when the link comes opposite the clearance, under the tension of the chain (Fig. 2). Of course when the chain has “recovered” from the stretch imposed thereon while passing the link 4 over the loop 3, 70 there will be a slight slack in the chain, but 75 not sufficient to at any time permit the ring 6 working out of the deep pocket b formed for its reception between the plate 1 and hook 2. A slight departure from the details here shown would not affect the nature 80 or spirit of our invention.

Having described our invention what we claim is—

In combination with a vehicle-wheel felly, a plate secured across the inner face of the 90 felly, a chain having an elongated link at one end and a circular ring at the opposite end, the plate terminating at one end in an open eye with a clearance between the plate and terminal of the loop forming the eye, 95 just sufficient to receive the elongated link aforesaid, the opposite end of the plate terminating in a hook disposed in the line of the axis of the plate and parallel to the plate, the hook being elongated to form a deep 100 pocket for the reception of the terminal ring of the chain and shaped so as to prevent said ring from being removed without first removing the elongated link, as set forth.

In testimony whereof we affix our signatures, in presence of two witnesses.

EDWARD P. HAFNER.
JOHN T. ROBERTS.
